UNITED STATES PATENT OFFICE.

WILLIAM STARLING BURGESS, OF MARBLEHEAD, MASSACHUSETTS, ASSIGNOR TO CURTISS AEROPLANE & MOTOR CORPORATION, A CORPORATION OF NEW YORK.

AEROPLANE-WING CONSTRUCTION.

1,285,021.

Specification of Letters Patent. Patented Nov. 19, 1918.

Application filed September 27, 1916. Serial No. 122,432.

To all whom it may concern:

Be it known that I, WILLIAM STARLING BURGESS, a citizen of the United States, residing at Marblehead, in the county of Essex and State of Massachusetts, have invented certain new and useful Improvements in Aeroplane-Wing Construction, of which the following is a specification.

My invention relates in general to aeroplanes and more particularly to the construction of the wings and ailerons thereof.

A feature of my invention is the attachment of the sets of superimposed wings or planes one to the other by means of wing posts carrying suitable hinged wing post sockets which will permit of folding the sets of wings upon each other in such manner that they will occupy a small space. This point is of great importance in facilitating the storage or shipment of the aeroplane wings without totally disassembling them.

The common or usual practice is to construct the ailerons and wings separately and attach the ailerons to the rearmost lateral wing beam, the trailing edge of the wing being cut away for this purpose. In my invention, however, I dispose the ailerons at a point somewhat aft of the usual position. To this end I utilize an auxiliary rear wing beam which I place at a point slightly to the rear of the main rear wing beam and preferably in line with the trailing edge of the remainder of the wing. To this auxiliary beam I attach the ailerons by means of suitable hinges or fastening devices. The ailerons are of such section that when attached to the wing and disposed at their normal or neutral position they so complement the frustum of the wing section as to present a perfect aerofoil in section. By thus shifting the position of the aileron rearwardly the chord of the wing at the aileron section is increased, and the attenuated wing section at this point produces an increased lift.

In accomplishing the folding wing feature of my invention the substantial innovation is that of placing the bolts which penetrate the wing post sockets so that the axes of said bolts are in a plane substantially perpendicular to the longitudinal axis of the wing beam instead of parallel thereto as is the current common practice. This permits of the wings folding down one upon

the other by simply releasing one set of stay wires.

Of the drawings:

Figure 1 is a plan view of a wing panel and aileron assembly; 60

Fig. 2 is a section along the line A—A, Fig. 1;

Fig. 3 is a section along the line B—B, Fig. 1;

Fig. 4 is an elevation of an assembly of 65 two wings;

Fig. 5 is a lateral view of a wing post socket, a part thereof being shown in section;

Fig. 6 is a front view of a wing post 70 socket, a part thereof being shown in section;

Fig. 7 is a side elevation of a biplane wing assembly in its normal and folding position. 75

In Fig. 1 let the outer or aileron panel of the wing be wholly designated as 10 and the inner panel or panels be wholly designated as 11. The aileron 12 is attached by means of hinges or other suitable fastening devices 13 to the rear auxiliary wing beam 14. The beam 14 is built into the wing at a suitable distance aft of the main rear wing beam 15. This auxiliary beam 14 abuts the web or rib 30, Fig. 2, and is held 80 in rigid contact therewith by means of the overlapping cap strips 31. This beam 14 serves as a means for attaching the hinges 13 and furthermore to preserve the desired strength of section required to withstand 85 the stresses due to the action of the ailerons carried by these hinges. The main rear wing beam 15 is of uniform depth for all sections along the entire wing as shown in Figs. 2 and 3. These figures also show 90 that at any given distance aft the main rear wing beam 15 as along the line C—C the panel 10 is thicker than the panel 11. This is to be expected, however, since the increase in effective chord attenuates the 95 wing section in order to preserve the aerofoil form.

The aileron 12 is constructed as shown at 12, Fig. 2, having a leading edge 32 of practically the same depth as the rear auxiliary wing beam 14, and a trailing edge 33 which is substantially the same as the trailing edge 34, Fig. 3, of the remainder of the wing sections. Hence when the aileron 12 is attached to the wing beam 14 and when 110

in its neutral position the entire section presents a practically unbroken aerofoil which so reduces the head resistance that the efficiency of the wing section at this point is materially increased. Moreover, this construction offers an increased effective chord at the aileron panel which results in an increased lift.

In Fig. 5 is shown a wing post extremity 16 attached to a male portion of the hinge 17 by means of the bolt 18. The base of the wing post socket which forms the female portion of the hinge is designated as 19. The two portions of the hinge or socket are 15 attached by means of the bolt or pin 20. The axis of the connecting pin or bolt 20 is substantially perpendicular to the axis of the wing beams and permits of radial movement of the wing posts about these pivotal 20 points in a plane substantially parallel to the lateral wing beams of the aeroplane structure.

In Fig. 6 the socket or hinge is shown sectioned along the line D—D, Fig. 5. The 25 clips to which are attached the stay or bracing wires are designated as 21, 22 and 23. These clips or eyelets may be stamped of metal and brazed or welded to the main base of the socket or may be held in place by 30 threading onto the bolt or pin 20.

The operation of my device is as follows: The wing 24, Fig. 4, and the wing 25 are held apart by means of the wing posts generally designated as 26 and are braced by 35 means of the wires or cables 27 and 28. To fold the wing 24 upon the wing 25 in the direction of the arrow 29 it is only necessary to loosen or release the stay wires 28 whereupon folding may be effected since the 40 wing posts 26 are pivotally connected at their extremities by means of the pins or bolts 20 as detailed in Figs. 5 and 6. The upper wing 24 will then occupy the position relative to wing 25 as shown in Fig. 7.

45 Although in disclosing the features and principles of my invention it has been necessary to enter into more or less detailed forms, for purposes of clarity, I do not consider my invention to be limited thereby. Moreover, my invention will apply equally 50 well to one, two or any plurality of planes or wings in any of several arrangements or superimposition.

What is claimed is:

55 1. An aeroplane wing structure comprising a body section and an aileron section, said aileron section being separately formed and having an enlarged rear beam substan-

tially aligned with the trailing edge of said body section and an aileron attached thereto. 60

2. An aeroplane wing comprising a body section of a cambered wing curve ending rearwardly in a sharp edge of inappreciable thickness as compared with the body thereof, an aileron section connected therewith 65 and terminating rearwardly in substantial alignment with said trailing edge in a beam of substantial thickness as compared with the thickness of the body of said section, together with an aileron connected to said 70 beam.

3. An aeroplane wing of determinate section having front and rear wing beams together with an auxiliary wing section having a beam of substantial size in the rear of 75 the rear beam of the body section, the auxiliary wing section having a similar but attenuated wing curve terminating rearwardly in the aileron itself.

4. An aeroplane wing comprising a body 80 section terminating rearwardly in a sharp edge of inappreciable thickness as compared with the body thereof, a trailing beam incorporated in the body section, an auxiliary section connected with the body section and 85 terminating rearwardly in a trailing beam of substantial thickness as compared with the thickness of the body of said section, and an aileron connected to said beam for continuing the auxiliary section rearwardly 90 to an edge of a thickness inappreciable as compared with the thickness of the aileron at or near its point of connection to said beam, the trailing beam of the aileron section and the trailing beam of the body section being unaligned. 95

5. An aeroplane wing comprising a body section of determinate wing curve having front and rear wing beams, the rear wing beam of the body section being forwardly 100 removed from its trailing edge, an aileron, and an auxiliary wing section of similar but attenuated wing curve terminating in the aileron itself, said auxiliary wing section likewise having front and rear beams respectively substantially aligned with the corresponding beams of the body section besides a third beam of substantial thickness in the rear of the rear wing beam for the attachment of the aileron. 105

In testimony whereof I affix my signature.

WILLIAM STARLING BURGESS.
